UNITED STATES PATENT OFFICE.

FRANK L. FURBUSH, OF WESTFORD, MASSACHUSETTS, ASSIGNEE TO C. G. SARGENT'S SONS CORPORATION, A CORPORATION OF MASSACHUSETTS.

YARN MOISTENER.

Application filed March 3, 1922. Serial No. 540,342.

To all whom it may concern:

Be it known that I, FRANK L. FURBUSH, a citizen of the United States, residing at Westford, in the county of Middlesex and 5 State of Massachusetts, have invented a new and useful Yarn Moistener, of which the following is a specification.

This invention relates to a machine for moistening yarn. The principal objects of 10 the invention are to provide a machine of the centrifugal type for moistening yarn wound on spools or bobbins or in the form of cops or balls for getting it into condition for subsequent operations.

15 The invention involves the provision of a rotary support for holding the yarn while it is being rotated, and means for introducing moisture into it at the same time in a fine spray and coming into contact with the inner surfaces originally so that the moisture will be spread throughout the yarn by 20 centrifugal force.

Reference is to be had to the accompanying drawings in which—

25 Fig. 1 is a vertical central sectional view of a yarn moistening device constructed in accordance with this invention;

Fig. 2 is a horizontal sectional view of the same on the line 2—2 of Fig. 1, and

30 Fig. 3 is a view similar to Fig. 1, showing modifications.

In the form shown in Figs. 1 and 2 I have provided a casing 10 having a bottom 11 for the machine. On this bottom is a step-bearing 35 12 carrying the bottom of a hollow shaft 13. This shaft is shown in these figures as being rotated by a belt 14 running on a pulley 15 at the top of the shaft, but in Fig. 3 a modification is indicated in which it is 40 driven at the bottom. At the top of this hollow shaft 13 there is a bearing and stuffing box 16 for supporting it at that end.

The casing 10 is provided inside with a rotary casing 17 fixed on the shaft 13. In this 45 rotary casing there are a plurality of radially arranged studs or the like 18 on which are mounted cops, bobbins, or spools 19 of wound yarn to be moistened. These studs are spaced around the circumference of the 50 inner rotary casing 17 in such a way that the cops or spools can be applied to them and they extend inwardly from the circumference.

Extending up from the top of the casing 55 10 there is an upper casing 20 on which

the bearing and stuffing box 16 are mounted. This is provided with a hollow head 21 at the top into which extends a pipe fitting 22 connected with a water supply pipe 23 and a steam supply pipe 24. These are provided 60 with valves 25 and 26 respectively. These valves are so manipulated as to cause the steam to force the water into the head 21 and down the pipe 13 and force it out of the perforations in the latter in the form of a 65 fine spray. The whole circumference of the pipe 13 within the casing 17 is perforated so that the spray will be uniform all around and from top to bottom. The casing 17 can be drained through openings 27 into the bottom of the outer casing 11 which is provided with drain pipes 28 for taking care of any 70 excess moisture.

In the form shown in Fig. 3, aside from the modification above mentioned, I have 75 shown a flexible supply pipe 32, otherwise both forms of the invention work in the same way.

The operation is very simple. The yarn is placed in position and the casing 17 with 80 the pipe 13 started into operation. The steam and water are regulated and introduced so as to force the water out in a fine spray mixed with steam into contact with the inner ends of the balls or cops. The 85 continued rotation acts to assist the action of capillary attraction by centrifugal force to lead the moisture clear to the center of each bobbin and clear to the outer end so that they will be moistened uniformly. Furthermore, if they should for any reason become 90 too moist the excess moisture will be thrown off at the circumference against the casing 17. The degree of moisture can be regulated by the valves 25 and 26, but it is 95 also regulated somewhat by the speed of rotation. In this way an accurate and easily regulatable method of moistening the yarn is provided.

Although I have illustrated and described 100 only two forms of the invention I am aware of the fact that other modifications can be made therein by any person skilled in the art without departing from the scope of the invention as expressed in the claims.

Therefore, I do not wish to be limited to all the details of construction herein shown and described, but what I do claim is:—

1. In a machine for moistening yarn, the combination of a rotary casing having means 110

for supporting a plurality of packages of yarn arranged at intervals around its circumference, and a central pipe about the center of which said casing rotates, provided with perforations and having means for introducing moisture through said perforations into the interior of said casing against the surfaces of the yarn.

2. In a machine for moistening yarn and the like, the combination of a central rotary hollow shaft or pipe, means for introducing steam and water into said pipe, means for rotating the pipe on its own axis, and means mounted on the pipe at a distance therefrom for supporting the yarn to be moistened.
3. In a machine for moistening yarn, the combination with a rotary pipe perforated for the escape of moisture, means for introducing water and steam into said pipe, means for rotating said pipe, and a support surrounding said pipe and rotating therewith for balls of yarn.
4. In a machine for moistening yarn, the combination of a stationary casing, a cover therefor, a hollow head at the top of said cover, pipes for introducing steam and water into said hollow head, means for regulating the relative amounts of water and steam in-

troduced, a stuffing box and bearing under said head, a vertical hollow shaft centered in said stuffing box and supported at the top by said bearing, means for rotating said shaft, a casing fixed on the bottom of said shaft and rotating therewith, said shaft having perforations therethrough throughout the height of said casing, and a plurality of radial studs projecting inwardly from the exterior of said casing for supporting balls of yarn.

5. In a machine for moistening yarn, the combination of a stationary casing, means for introducing steam and water into said casing, a hollow shaft extending through said casing, means for rotating said shaft, an inner casing fixed on said shaft to rotate therewith, said shaft having perforations therethrough throughout the height of the inner casing, and a plurality of radial studs projecting inwardly from said inner casing toward the shaft for supporting balls of yarn in a position to be moistened by water and steam forced out through said perforations.

In testimony whereof I have hereunto affixed my signature.

FRANK L. FURBUSH.
